(57) **CLAIM**

The ornamental design for a hose connector, as shown and described.

DESCRIPTION

FIG. 1 is a perspective view of the hose connector.

FIG. 2 is a left side elevation view of the hose connector.

FIG. 3 is a right side elevation view of the hose connector.

FIG. 4 is a front elevation view of the hose connector.

FIG. 5 is a back elevation view of the hose connector.

FIG. 6 is a top plan view of the hose connector.

FIG. 7 is a bottom plan view of the hose connector.

FIG. 8 is a perspective view similar to FIG. 1, but adding an optional cover shown in broken lines.

FIG. 9 is a left side elevation view similar to FIG. 2, but adding an optional cover shown in broken lines; and,

FIG. 10 is a right side elevation view similar to FIG. 3, but adding an optional cover shown in broken lines.

Broken line is included for the purpose of illustrating portions of the hose connector and an optional cover and forms no part of the claimed design.
